WIRE SPRING FOR CUSHIONED SEATS OF UPHOLSTERED FURNITURE

William H. Neely, Cleveland, Ohio, assignor, by direct and mesne assignments, to John C. Lincoln, Scottsdale, Ariz.

Application February 14, 1939, Serial No. 256,277

10 Claims. (Cl. 155—179)

This invention relates in general to springs and spring seat structures for upholstered furniture and more particularly to flat springs of sinuous or similar shape such as described in Patent No. 2,047,411. These springs, each of which consist of a substantially straight seating or resting portion, an integral rearwardly and downwardly inclined front supporting arm and an integral coiled portion at the rear end of the seating or resting portion when rigidly attached to a frame, develop under load undesirable stiffness in an area near or adjacent to the rear end of the seating or resting portion. This stiffness which is due to excessive bending stresses in such area very materially interferes with proper seating and resting comfort on seat structures embodying the described type of springs.

The primary object of the present invention is to provide an improved corrugated wire spring of the type referred to above which embodies means eliminating from the proper seating surface the area of undesirable stiffness so as to permit of proper seating and resting comfort on seat structures assembled from the wire springs according to the invention.

Another object of the invention is the provision of a spring of the type referred to having a corrugated, substantially straight seating portion supported by rearwardly and downwardly inclined front supporting means and a rearwardly and upwardly inclined rear supporting means, said supporting means including means for rigidly attaching same to a frame structure.

A further object of the invention is to provide a spring having a corrugated, substantially straight seating portion supported by specific front and rear supporting and attachment means, which spring includes means intermediate its seating portion and the rear supporting and attachment means for effecting a downward offset of the rear end of the seating portion with respect to the rear attachment and supporting means, thus avoiding undesirable upward bulging of the rear end of the seating portion into the seating plane by any and all bending stresses in said seating portion when the spring is loaded.

Still another object of the invention is the provision of a spring of the type described above with a seating portion and attachment means including coiled portions, the attachment means being arranged with respect to the seating portion, so that said portion is slightly stretched and bulged when the spring is rigidly secured to a frame and the spring including means arranged between the seating portion and the rear attach-

ment means for effecting a downward offset of the rear end of the said seating portion to avoid upward bulging of the rear end of the spring when secured to a frame and when under load.

5 In addition, the invention has other marked improvements and superiorities which radically distinguish it from presently known structures. These improvements or superior characteristics embodying certain novel features of construction are clearly set forth in the appended claims, and a preferred embodiment of the invention is hereinafter shown with reference to the accompanying drawing, forming part of the specification.

In the drawing:

Fig. 1 is a vertical sectional view through a spring seat structure showing a metal seat frame having corrugated springs made according to the invention securely fastened to the seating portion of the frame.

Fig. 2 is a perspective view of one of the elongated springs forming the seat structure shown in Fig. 1; and

Fig. 3 is a diagrammatical view showing the different shapes of the elongated spring according to the invention under different loads.

Referring now in detail to the exemplified form of the seat structure shown in the drawing reference numeral 2 indicates an open tubular frame structure which is made of tubular piping and embodies a front rail 3, a side rail 4 and a back rail 5. Front and rear rails 3 and 5 support a plurality of elongated, corrugated wire springs 6 which bridge frame 2 crosswise and are securely attached to said rails in a manner hereinafter to be described.

The elongated corrugated springs 6 are made of steel wire, bent to sinuous shape, so that their loops 7 extend substantially parallel to each other and permit of longitudinal yielding stretching of the springs under load. The front end of each spring 6 is formed with an integral, rearwardly and downwardly extended supporting arm 8 which is looped at its lower end to provide a spring coil 9, arranged in a plane substantially rectangular to the plane of spring 6. The end of coil 9 extends forward as at 10 from the bottom of said coil and is then looped preferably in opposite direction with respect to coil 9 to form a second coil 11, which latter coil is downwardly extended from portion 10 in a plane also substantially rectangular to the plane of the spring. Coil 11 has a free straight end portion 12, preferably forwardly and laterally extended from the top of said coil at an angle to the axis of spring 6 and this portion 12 is doubled back in definite

spaced relation with respect to coil 11 to form a hook-shaped member 14 adapted to rigidly secure spring 6 to tubular front rail 3, which rail has for such purpose holes 15 arranged therein, all, as more clearly brought out in co-pending application Ser. No. 215,526 of which applicant is co-inventor.

The rear end of spring 6 is bent upwardly as at 16 on a curvature and then curved upwardly in opposite direction to form a lever 17 having at its end a hook-shaped attachment means 18 integrally extended therefrom. This attachment means embodies a coil 19 and a hook 20 similar to the attachment means at front supporting arm 8, therefore no further description of attachment means 18 are deemed necessary. The upwardly and rearwardly extended lever 17 effects a downward offset of the rear end of spring 6, when such spring is secured or attached to the front and back rails 3 and 5 of frame 2, back rail 5 being provided with holes 21 similar to holes 15 in front rail 3, thus permitting interlocking engagement of rear attachment means 18 with rail 5.

Springs 6, when assembled to a seat structure as customary, are interconnected by an edge wire 22 and form a continuous seating surface which is preferably covered by a pad and covering indicated in dotted lines at 23. Proper mounting of springs 6 on frame 2 is effected by arranging rear rail 5 of frame 2 in an elevated position with respect to front rail 3. This construction leaves an open space below said rail and permits of building of a front seat construction which in automobiles with front and back seats provides ample space to insure comfortable rest for persons in the back seat even when the space between the front and back seats is limited.

A seat structure embodying springs of the type described provides a perfect comfortable seat under all conditions, as will best be understood from an inspection of the diagrammatical showing of Fig. 3, which figure discloses shape and deformation of a spring structure with springs according to the invention when differently loaded. The full line showing *a* of the spring outline in Fig. 3 is the shape taken by the spring when not loaded. In this shape which shows a slight curve in the seating portion of spring 6, the curvature of the seating portion is effected by the tension of the coil in the rear attachment means 18, which latter is interlocked with rear rail 5 of frame 2. Please note that the said coil is tensioned and therefore effects the slight upward bulge and, in addition, a slight longitudinal tension in loops 7 of spring 6.

The next diagrammatically shown shape and deformation of the spring shown in Fig. 3, the dotted line position *b*, is effected when a light load is carried by spring 6. It is of course to be understood that all the springs of a spring seat structure are either interconnected by edge wires and connecting means such as disclosed in the above referred to application or are interconnected in any other suitable manner and furthermore are covered by a padding, so that the load is carried by an extended area of the seat structure. Dotted line position *b* of the spring shows flattening of the curvature of the spring, a slight longitudinal elongation of the spring which effects a slight increase in the tensioning of loops 7, and an increase in the tensioning of the coils in the rear and front attachment means, which tensioning effects a slight increase in the angle between lever 17 and the seating portion of the

spring. Special attention, however, is called to the fact that an upward bulge of spring 6 cannot and does not occur.

The following diagrammatically shown shape and deformation of the spring shown in Fig. 3, the dash-dotted line position *c*, is effected when a heavier load is carried by the spring. This position *c* shows practically no curvature in the resting position of the spring which has been further elongated with a further increase in the tensioning of loops 7 and which has the coils in rear and front attachment means also further tensioned, so that substantial resistance is built up against downward bulging of the seating portion. Such resistance is additionally due to the further flattening of the angle of lever 17 with the seating portion of the spring, however, this angle is still of sufficient size to prevent upward bulging of the spring and thus insures proper riding comfort on the seat structure. Attention is called to the fact that the dash-dotted line position *c* approximates the general shape of springs supporting a person of average weight.

The last diagrammatically shown shape and deformation of the spring shown in Fig. 3, the dash-dotted line position *d*, is effected when sudden excessive loads are imposed on the springs, for example, when an automobile equipped with a seat structure embodying this type of springs is driven over excessive bumpy roads. Dash-dotted line *d* indicates a change in the curvature of the seating portion of the spring to a slight S-curve with the change from one curve into the other, approximately located in the central area of the seating portion, so that the rear portion of the seating portion, which rear portion actually supports the load, is bulged slightly downward. In addition, the excessive load has tensioned the coils of the attachment means, effecting a substantial lengthening of the seating portion of the spring and, as the seating portion and its loops 7 are under substantial tension, sufficient resistance has been built up in the seating portion to resist further downward movement of the seating portion under these excessive loads, which portion will hereafter give only slightly under still heavier loads.

It can now be seen that spring structures embodying springs of the type described offer utmost riding and seating comfort, due to the fact, that their seating surfaces under load do not materially change or form excessive hard areas and that such surfaces possess under adverse conditions sufficient yielding action in their front edges to permit of proper support and simultaneously sufficient yield.

Having thus described my invention, what I claim is:

1. A wire spring for seat structures comprising a horizontally corrugated seating portion, an integral rearwardly and downwardly extending yielding lever arm extending from the front end of said seating portion, and an integral supporting and attaching means extending from the rear end of said seating portion in upwardly offset relation with respect to the axis of said seating portion.

2. A wire spring for seat structures comprising a horizontally corrugated seating portion, an integral rearwardly and downwardly extending yielding lever arm extending from the front end of said seating portion, an upwardly and rearwardly inclined short lever extending from the rear end of said seating portion and integral at-

tachment means at the free ends of said lever arm and said lever.

3. A wire spring for seat structures comprising a horizontally corrugated seating portion, an integral rearwardly and downwardly extending yielding lever arm extending from the front end of said seating portion, an integral upwardly and rearwardly inclined, slightly S-curved lever extending from the rear end of said seating portion and integral attachment means at the free ends of said lever arm and said lever.

4. A wire spring for seat structures comprising a horizontally corrugated seating portion, an integral rearwardly and downwardly extended yielding lever arm extending from the front end of said seating portion, an integral coil arranged above the surface of said seating portion and extended from the rear end thereof, integral attachment means at the end of said lever arm and integral hook-shaped means extending from the end of said coil in angular relation with respect to the axis of the seating portion of said spring.

5. A wire spring for seat structures comprising a horizontally corrugated seating portion, an integral rearwardly and downwardly extended yielding V-shaped lever arm extending from the front end of said seating portion, and integral hook-shaped attachment means including a coiled portion and extending from the rear end of said seating portion in upwardly offset relation with respect to the axis of said seating portion.

6. As an article of manufacture and sale a cushioned seat for automobiles comprising a frame and a plurality of springs bridging said frame and rigidly secured thereto crosswise thereof, each of said springs embodying a horizontally corrugated seating portion, an integral rearwardly and downwardly extended yielding lever arm extending from one end of said seating portion, a coil integrally extended from the other end of said seating portion and arranged in a plane above the surface of said seating portion rearwardly thereof and attachment means on the free end of said lever arm and said coil, the upward and rearward arrangement of said coil preventing undesired stiff areas being upwardly extended near said other end of said seating portion when said spring is under load.

7. An article of manufacture and sale as described in claim 6, wherein said attachment means are angularly related to each other so

that a torsion is applied to the lever arm and coil in a direction to effect stretching and bulging the seating portion of the springs to provide sufficient initial resistance in said seating portions against downward bulging under load.

5 8. A wire spring for seat structures comprising a corrugated, axially yielding continuous seating portion, supporting means integrally and freely extending downwardly and rearwardly from one end of said corrugated seating portion, attachment means integrally extended from said supporting means, supporting means integrally and freely extending upwardly from the other end of said corrugated seating portion, and attachment means integrally extended from said last supporting means.

9. A wire spring for seat structures comprising a corrugated seating portion, downwardly and rearwardly extended integral lever means at the front end of said seating portion, integral means on said lever means for rigidly securing same to a frame, and integral yielding means for supporting the rear end of said seating portion, said last means including attachment means for rigidly securing said rear end to such frame, and means integrally extended from said seating portion in upwardly directed relationship with respect thereto forming an upwardly curved bend between said seating portion and its rear supporting means, said bend counteracting upward bulging of said seating portion adjacent to said bend when said spring is secured to a frame and said seating portion is moved downwardly by a load placed thereon.

35 10. As an article of manufacture and sale a cushioned seat for automobiles comprising a frame and a plurality of springs bridging said frame and rigidly secured thereto crosswise thereof, each of said springs embodying a horizontally corrugated, axially yielding seating portion, an integral rearwardly and downwardly extended yielding lever arm extending from one end of said seating portion, an integral upwardly and rearwardly inclined short lever extending from the other end of said seating portion, and attachment means integrally extended from the free ends of said levers, the upward and rearward arrangement of said short lever preventing undesired stiff areas being upwardly extended near said other end of said seating portion when a load is placed on the spring.
